PERPETUAL CALENDAR

Jaime Röltman, Rosario, Argentina

Application November 14, 1942, Serial No. 465,611
In Argentina December 30, 1941

5 Claims. (Cl. 40—114)

The present invention relates to calendars, and more particularly to calendars of the type known as "perpetual," which are designed to be utilizable over a period of years without requiring replacement of the date and/or year indicating portion.

The known types of perpetual calendars may roughly be divided into two broad classes, namely, those consisting of a single disc mounted to rotate about its center and having printed on its circular surface a plurality of sets of numbers of the days of the month, or else a plurality of year numbers disposed in a special arrangement so that by setting the disc with respect to an indicating point the calendar may be adjusted to give the correct dates for all the months of the particular year or else for a particular month of a particular year. The second class of known perpetual calendars comprises apparatus including separate indicating means for the date, the day of the week, the month and the year, and these means are adapted to be individually operated.

The present invention is more especially concerned with the second class of calendars to which reference has just been made. In the known constructions, it is necessary to make a daily adjustment for the date, that is to say, the day of the week and its number, this adjustment involving two operations. At the end of each month the monthly adjustment, and at the end of each year the yearly adjustment, must be made. Hence the process of keeping the calendar up to date in this type of device is troublesome, requires daily attention, and is usually a manual operation. Some attempts have been made to provide mechanically operated calendars of this type in which the month indication has been coupled by gearing or the like to the day and number indications, but the known devices of this mechanical kind have been comparatively complicated and costly or else have been incomplete as regards the automaticity of some of the adjustments in dependence on the day to day adjustment.

It is therefore a principal object of the present invention to provide an improved and novel device of the kind described in which it shall be possible to secure an automatic adjustment of all the factors over a considerable period of years substantially by means of a single actuating movement per day.

A further object of the present invention is to provide a semi-automatic or automatic perpetual calendar which comprises compensating

means for compensating the adjustment operation of the device automatically with respect to the varying numbers of days in the months including variations in the number of days of the month of February for leap years and non-leap years.

A further object of the present invention is to provide a perpetual calendar of the type described which shall be easy and cheap to construct, reliable in its operation and embodies either as an independent unit or as part of a clock or the like.

Another object of the present invention is to provide a calendar device of the kind described including electrically operated actuating members, the electrical portion being arranged so that it may be connected permanently to a source of current through a time switch, or alternatively connected through a push button or the like either to the mains or to a portable source of current, for manual operation.

These and other objects and advantages of the present invention will become apparent in the course of the following detailed description of a preferred embodiment thereof illustrated in the accompanying drawings, in which,

Fig. 1 is an elevation partly in section of the essential mechanical parts of my novel calendar, with certain parts, including the electrical circuits omitted for clarity.

Fig. 2 is a top plan view of the main electro-mechanical actuating members of the apparatus of Fig. 1.

Fig. 3 is a detail end elevation of the year counter.

Fig. 4 is a detail of certain parts seen after sectioning the calendar on the line IV—IV of Fig. 1.

Fig. 5 is a detail view of certain parts seen after sectioning the device on the line V—V of Fig. 1, with certain other parts displaced from the position shown in Fig. 1, for clearness.

Figs. 6 and 7 are detailed views of certain parts seen after sectioning the device along the lines VI—VI and VII—VII of Fig. 1, and

Fig. 8 is a diagram showing the connections of the electrical actuating portion of the device.

In all the figures the same reference characters indicate like or corresponding parts.

In Fig. 1, I have shown the essential mechanical working parts of my novel calendar embodied as a vertical type device, although it is to be understood that the device may equally readily be embodied so that the main operating shafts are normally in horizontal position. In

the example shown the number of the year, the name of the month, and the number and name of the day are shown vertically superposed and each line is read horizontally. In a horizontal embodiment, these indications would be arranged in side by side relationship for vertical reading of each line. The working parts together with the electrical actuating members are preferably enclosed in a housing (not shown) which has transparent portions positioned suitably to indicate reading positions for the year, month, day number and day name.

As shown, the mechanism comprises a central shaft 1 mounted for rotation in suitable bearings (not shown). Near its lower end said shaft has fast on it a disc 2 the periphery of which is divided into seven equal parts and has applied thereto in any suitable manner the names of the days of one week. Above the disc 2 an intermediate hollow shaft 3 is concentrically mounted for rotation on the shaft 1. Said intermediate hollow shaft 3 has fast on it in the neighborhood of its lower end a number disc 4 the periphery of which is divided into 31 equal parts and bears numerals from 1 to 31 inclusive which are intended to give the number of the day in the month.

Above the number disc 4 an outer hollow shaft 5 is concentrically mounted for rotation on the intermediate hollow shaft 3, and said outer hollow shaft has fast on it in the neighborhood of its lower end a month disc 6 the periphery of which is divided into 12 equal parts and bears indications of the months of one year.

Above the month disc 6 there is mounted independently of the shafts 1, 3, and 5, by any suitable means (not shown) a decimal counter for 4 figures of any convenient known type, so that the reading of the counter shall be parallel to the discs 2, 4, and 6. Preferably the discs and the counter are so arranged that the indicia corresponding to a particular date, are, when brought into indicating position as hereinafter explained, symmetrically disposed with respect to a common vertical center line. It is, however, also possible, particularly if a cylindrical casing is used to enclose the device, to arrange for the indicia to appear in staggered or doubly staggered formation.

The central shaft 1 has fast on it near its end remote from the disc 2, a ratchet wheel 8 having 7 teeth corresponding to the seven days of the week, so that this ratchet wheel will hereinafter be referred to as the day ratchet. Similarly the intermediate hollow shaft 3 has fast in the neighborhood of its end remote from the disc 4 another ratchet wheel 9 provided with 31 teeth and hereinafter called the number ratchet.

As best seen in Fig. 2, I provide for operation of the day and number ratchets a pawl carrying arm 12 pivotally mounted on one end to some convenient point of the enclosure (not shown) of the mechanism. Said arm 12 has pivotally mounted on it in spaced relation a pair of pawls 10 and 11 fitted with the usual pawl springs 10a, 11a, and spring urged normally into engagement with the teeth of the ratchets 8 and 9 respectively by means of a spring 13 extending between a suitable fixed point 13a and the free end of the arm 12. At a point intermediate the pawl 10 and the pivoted end of the arm 12, I provide a plunger 14 pivotally secured to said arm 12 to extend into a main solenoid 15 adapted to be energized in a manner to be hereinafter explained, for the ordinary actuation of the calendar device.

In order to provide compensation for the variations in the numbers of days in the months, I provide a second pawl arm 17 hereinafter referred to as the compensating arm, which is pivoted at one end to a suitable fixed portion of the housing, and at a point intermediate its ends has pivoted to it a compensating pawl 16, provided with the usual pawl spring 16a and spring urged into engagement with the teeth of the number ratchet 9 by means of a coil spring 18 extending between a fixed point 18a and a point on the compensating arm 17 on the side of the compensating pawl remote from the pivoted end of the compensating arm 17. The other end of said arm 17 has pivoted to it a plunger 19a which extends into a compensating solenoid 19. Said compensating solenoid is adapted to be energized only at certain times as will hereinafter be more fully explained. The compensating pawl 16 engages the teeth of the number ratchet in such a manner that it will drive the ratchet wheel 9 in the same direction as will the pawl 11.

The parts are so proportioned that for one reciprocation of the arm 12 in response to a momentary energization of the main solenoid 15 and the restoring action of the spring 13, both the ratchets 8 and 9 are rotated together through one tooth pitch, and that similarly one reciprocation of the compensating arm 17 will rotate the number ratchet 9 through one tooth pitch independently of the day ratchet 8. It will be obvious that with the arrangement described, a rotation through one tooth pitch of the ratchets 8 and 9 will cause the respective discs 2 and 4 to rotate (from right to left in Fig. 1) through $\frac{1}{7}$ and $\frac{1}{31}$ of their circumferences respectively whereby to cause a shift in the indicia so that the next higher number (or the commencement of the number cycle) and the name of the next day of the week will then appear in reading position, in the embodiment shown, symmetrically disposed about the common vertical center line. Suitable braking means for holding the ratchets in position and preventing overrunning are also provided, although I have not illustrated them as I deem their construction and operation to be sufficiently familiar to those skilled in the art to require no detailed description.

At the end of the outer hollow shaft 5 remote from the month disc 6 I provide a month ratchet wheel 25 and for intermittent actuation thereof I provide on the intermediate hollow shaft 3 between the number ratchet 9 and said month ratchet 25 a spiral cam 20 fast on said intermediate shaft 3. As best seen in Fig. 4, I further provide an actuating arm 22 pivoted at one end to a suitable part of the housing, and provided at an intermediate point with a laterally projecting stop 21 normally spring urged into engagement with the cam surface of the cam 20 by means of a coil spring 23 extending between a fixed point 23a and the free end of the actuating arm 22. Intermediate the stop 21 and the free end of the actuating arm 22, there is pivoted to said arm a month pawl 24 fitted with its pawl spring 24a and urged by the same spring 23 into engagement normally with teeth of the month ratchet 25, the number of said teeth being 12. The spiral cam 20 has at one point a shoulder 20a extending radially between the radially nearest and furthest points of the cam surface with respect to the center line of the hollow shaft 3. The spiral cam 20 is positioned on the shaft 3 so that the shoulder corresponds to the position

of the number "31" on the number disc 4, whereby, when the number disc indicates 1st of any month, the stop 21 engages the portion of the cam surface radially nearest to the center of the shaft 3. As said shaft 3 is rotated in the direction of the arrow *a* in Fig. 4, the cam surface moving under the tooth 21 will gradually cause the arm 22 to move away from the hollow shaft 3 and hence from the ratchet wheel 25, by turning about its pivot. The arrangement is such that when the shoulder 20a is separated from the tooth 21, in the direction opposite to that of rotation, a distance equal to one tooth pitch of the month ratchet 25, the number disc indicates the 30th of a month. When the shoulder 20a is under the stop 21, the number disc indicates the 31st and the month pawl 24 has cleared the ratchet tooth with which it was engaged and has been swung, to the left in Fig. 4, by the pawl spring 24a into position to engage the next tooth reckoning in a direction opposite to the rotation of the cam 20. The effective engagement of the month pawl 24 with said next tooth occurs as soon as the shoulder 20a clears the stop 21, to allow the spring 23 to pull the actuating arm 22 towards the cam 20 and month ratchet 25. As the actuating arm 22 moves towards the ratchet 25 under the pull of the spring 23, the pawl 24 rotates the month ratchet 25 through one tooth pitch thus changing the month indication to that for the following month. The shoulder 20a clears the stop 21 when the calendar is actuated at midnight on the last day of a month to change the number indication to "1."

In a somewhat similar manner the counter 7 is actuated once every year by means of a spiral year cam 26 fast on the outer hollow shaft 5. As best seen in Fig. 5 an arm 27 pivoted at one end to a suitable part of the housing has a laterally projecting stop 27a which is spring urged into contact with the cam surface of the year cam 26 by means of a spring 28 anchored at one end to a fixed point 28a and at the other end to the free end of the arm 27. At a point intermediate the stop 27a and the free end of the arm 27 one end of a counter actuating rod 29 is pivoted, said rod having its other end connected to an arm 30 mounted on the spindle of the counter 7 and provided with a pawl 31 which engages a counter ratchet wheel 32. From the description given above in connection with Fig. 4, the operation of the year cam 26 will be readily understood. The cam surface of the year cam 26 as it rotates in the direction of the arrow under the stop 27a gradually raises the arm 27 with respect to the counter 7 and thereby moves the pawl 31 (see Fig. 3) into a position to clear the tooth with which it is engaged and to engage the next tooth as soon as the shoulder 26a of the year cam has cleared the stop 27a, the movement of the arm 27 being transmitted to the pawl 31 through the rod 29 and arm 30. Since there is only one shoulder for the cam 26 and the hollow shaft 5 is rotated step by step once a month, and since a full rotation thereof is completed in 12 steps by reason of the 12 teeth on the month ratchet 25, it follows that the year cam 26 which is fast on the hollow shaft 5 will cause operation of the counter once a year to increase the total number shown by the counter by one unit.

The arrangement so far described would only serve in practice if every month had an equal number of days. Consequently, certain compensating devices have to be introduced to allow

for a double operation in one day of the number disc so as to jump the number "31" for thirty day months, four successive operations of the number disc at the end of the month of February, and a triple operation of the number disc for leap years at the end of February. These compensating devices will now be described.

The compensation is effected as indicated above by causing the arm 17 (Fig. 2) to move the number ratchet 9 through the required extra number of tooth pitches immediately following a daily operation of the arm 12. This involves energization of the compensating solenoid 19 and properly timed energization of this solenoid is insured, in the first place, by a contact making arm 33 fast on the intermediate shaft 3 and extending radially therefrom. Said contact making arm 33 cooperates with three pairs of normally open contacts 29c, 30c, and 31c (best seen in Fig. 8), of which only the pair 30c is shown in Fig. 1. Said pairs of normally open contacts are located in the path of the free end of the contact making arm 33, which may be entirely of electro-conductive material, or may have merely a tip portion of such material. The pairs of normally open contacts are arranged along an arc of the circular travel of the contact making arm 33 and are spaced apart so that their center points are separated by a tooth pitch of the number ratchet 9. Relatively to the number disc, the contact making arm 33 and the cooperating pairs of normally open contacts 29c, 30c, and 31c, are disposed so that when rotating in the direction of the arrow *a* in Fig. 7 the arm 33 will bridge the contacts 29c when the number "29" appears in the assigned position for indicating the date, and said arm will successively bridge the pairs of contacts 30c and 31c when the numbers "30" and "31" appear in said assigned position.

The said pairs of contacts 29c, 30c, and 31c, which as shown may be leaf spring contacts extending from a mounting 34 of insulating material, are the number compensating contacts, but since the compensation must be irregularly distributed over the year, a month selector device is incorporated in my calendar. The month selector consists of a disc 35 fast on the outer hollow shaft 5 and provided with five radially projecting teeth 36, 36a, (see Figs. 1 and 6) spaced around the circumference of the disc 35 to agree with the circumferential spacing of the thirty day months and the month of February on the month disc 6. The tooth 36a corresponding to the month of February has a depending extension 36' (Figs. 1, 6 and 8). The selector teeth 36, 36a cooperate with a pair of normally open short month contacts 37 and the depending extension 36' cooperates with a second pair of normally open February contacts 38 mounted below the pair 37. Depending on the location of the pairs of contacts 37 and 38, the selector teeth may be positioned in circumferentially staggered relationship with respect to the corresponding month disc 6.

As will presently be seen, the compensating arrangement 33 with the associated contacts 29c, 30c, and 31c, and the selector arrangement enable all the necessary compensations to be automatically effected with the exception of the compensation for February in leap years. The leap year compensating means comprises a pinion 40 fast on the hollow shaft 5 and meshing with a toothed wheel 41 in a ratio of 4 to 1, said toothed wheel being mounted for rotation on a pin 42

and having mounted thereon a contact breaking member 43, for example a piece of insulating material, which projects radially beyond the tooth wheel 41 and cooperates once every four years with a pair of normally closed control contacts 44, which may, for example, consist of a pair of leaf spring members anchored to a supporting block 45 which may, if desired, form part of the enclosing structure.

Referring now to Fig. 8, the compensating solenoid 19 is connected at once end to line through make and break contacts 46 designed to break the energizing circuit of the compensating solenoid when the latter has been energized so as to permit of a further energization thereof. The other end of the solenoid 19 is connected by conductor 47 and branch conductors 48, 49 to one side of the pairs of normally open contacts 30c and 31c, and also by a parallel branch circuit comprising conductor 50, normally closed control contacts 44 and conductor 51 to one side of the normally open pair of contacts 29c. The other sides of the pairs of normally open contacts 29c and 30c are connected in parallel by conductors 52 and 53 to one side of the pair of normally open February contacts 38. The other side of the pair of normally open contacts 31c is connected by conductor 54 to one side of the pair of normally open short month contacts 37, and the other sides of the pairs of said normally open contacts 37 and 38 are connected in parallel by conductors 55 and 56 to the other side of the line. The main solenoid 15 (Fig. 2) is connected across line through a time switch or general energizing device (not shown) which may, as stated above, be a push button if manual operation of the calendar is desired. The time switch may be incorporated as part of a clock, and in such form the novel device may be arranged to indicate the time as well as the correct date.

The ordinary operation of the device will be readily understood from the hereinabove given description relating to Figs. 2, 3, 4 and 5, actuation of the device taking place at midnight of each day by operation of the time switch or of the push button as the case may be. Normally the closure of the main circuit by the time switch or push button will energize only the solenoid 15 since the compensating solenoid 19 is open circuited at the contacts 29c, 30c, and 31c on all days from the first to the twenty eighth of the month. In a month having 31 days compensating solenoid 19 remains open circuited in spite of the bridging of the pairs of contacts 29c, 30c, and 31c successively by the arm 33 when said arm moves into the position in which the number disc 4 indicates the 29th, 30th, and 31st of the month, because the pairs of contacts 37 and 38 will not be bridged by a tooth of the month selector 35. In a 30 day month, however, the pair of short month contacts 37 will be bridged by a tooth 36 when the arm 33 moves into position to bridge the normally open contacts 31c, so that in these circumstances at midnight on the 30th after the time switch has acted to move the indicating parts of the calendar into the position of showing the 31st of the current month, an energizing circuit for the compensating solenoid is established from one pole of the line through make and break switch 46, solenoid 19, conductors 47 and 49, bridged contacts 31c, conductor 54, bridged short month contacts 37, and conductor 56 to the other side of the line. Energization of the compensating solenoid 19 attracts the plunger 19a (Fig. 1)

whereby, as hereinabove explained, the compensating arm 17 acts to move the number ratchet 9 through a further tooth pitch thus causing the number "1" to appear in the indicating position.

- 5 This movement of the number disc 4 causes the shoulder 20a of the month cam 20 to clear the stop 21 thereby entailing rotating of the month ratchet 25 through one tooth pitch as explained above to change the month indication, thereby 10 also causing the respective tooth 36 to move away from the short month contacts 37 to prevent re-energization of the compensating solenoid 19 until said contacts are again bridged. It should be noted that movement of the number ratchet 9 consequent on energization of the compensating solenoid 19 does not involve movement of the day ratchet 8 which is actuated only by the main solenoid 15. Hence during the number compensation, the day adjustment already 15 made by operation of solenoid 15 remains unaltered.

In Fig. 8 the parts are shown just after actuation of the time switch at midnight on February the 28th, when the contacts 29c are bridged by 25 the arm 33 and both the pairs of contacts 37 and 38 are bridged by the February tooth 36a and its depending extension 36'. At this time an energizing circuit is established for the compensating solenoid 19 from one pole of the line 30 through the make and break contacts 46, solenoid 19, conductors 47 and 50, normally closed leap year contacts 44, conductor 51, bridged contacts 29c, conductors 52 and 53, bridged February contacts 38, conductors 55 and 56 to the other pole 35 of the line. As already explained energization of the compensating solenoid 19 causes the number ratchet 9 to be moved through one tooth pitch so that the number disc and consequently the arm 33 will be moved from the position indicating the 29th to the position indicating the 30th, in which position contacts 30c will now be bridged by arm 33, the two pairs of contacts 37 and 38 remaining bridged as just explained because the month indicated is still February (since shoulder 20a of the month cam 20 is operative only during transition from 31st to 1st) and therefore the month selector disc remains in the described position. The energization of the compensating solenoid 19 just described is automatically broken 45 by the make and break contacts 46 so that when the arm 33 bridges the contacts 30c the compensating solenoid 19 may again be energized through the circuit extending from one pole of the line to make and break contacts 46, solenoid 19, conductors 47 and 48, bridged contacts 30c, conductor 53, bridged February contacts 38 and conductors 55 and 56 to the other pole of the line. Consequently, the number ratchet 9 will be moved 50 to a further tooth pitch to bring the number disc 4 to a position indicating the 31st, when the arm 33 will bridge the contacts 31c to establish the energizing circuit for the compensating solenoid 19 through the bridged short month contact 37 as already described above in connection with a 55 30 day month. This last energization of the compensating solenoid 19 moves the parts into the position to indicate the 1st of March and therefore causes arm 33 to leave the contacts 31c thereby establishing the open circuit condition for the solenoid 19 until the end of the next thirty day month, since by changing the month indication from February to March which occurs 60 when the number disc moves from the position indicating the 31st to that indicating the 1st, as just explained, the February tooth 36a with its 65 70 75

depending extension 36' is moved away from the pairs of contacts 37 and 38, to break the energizing circuit of solenoid 19 until the next short month (April).

In a leap year when the parts are in the position shown in Fig. 8 the normally closed leap year contacts 44 are opened by the contact breaking member 43 which will reach its operative position once every four years owing to the reduction gear connection of 4 to 1 between the outer hollow shaft 5 which carries the month disc 6 and therefore makes one complete revolution in twelve months, and the toothed wheel 41 which carries the contact breaking member 43. Thus although at midnight on February 28th in a leap year the arm 33 moves to bridge the contacts 29c, and hence normally to establish the energizing circuit for the compensating solenoid 19 as explained above, this energizing circuit cannot be established by reason of the open condition of the normally closed leap year contacts 44. Hence the calendar will remain at the indication "February 29." At midnight on the 29th the arm 33 is moved consequent on energization of the main solenoid 15, to bridge the contacts 30c, and since the energizing circuit established between this pair of contacts shunts the contacts 44, the device will operate as above described to jump the dates 30th and 31st by two successive actuations of the compensating solenoid 19.

It will of course be understood that the successive energizations of the compensating solenoid 19 take place immediately after the arm 33 has moved into position to establish the energizing circuit, that is to say, immediately after midnight of the day in question, so that a few seconds after midnight the proper indication following on February or a 30 day month will have been established.

As will be noted from the above description, the internal operation of my novel calendar is automatic to establish the proper sequence of changes in the day, the day number, the month, and the year, including the variations during a year and the variations for leap years. It will also be understood that by using a time switch for energization of the main solenoid 15 once in every 24 hours, fully automatic operation of the calendar can be obtained, whereas it is also possible to make the device semi-automatic by providing for push button instead of time switch operation.

Although I have described my novel calendar with particular reference to a preferred embodiment it is to be understood that various changes and modifications may be made therein without departing from the spirit and scope of the present invention as defined in the appended claims.

I claim:

1. An electrically operated perpetual calendar comprising rotary day indicating means and rotary number indicating means bearing the numbers from 1 to 31, electrically operable actuating means including ratchet means arranged to rotate said day and said number indicating means simultaneously step by step, rotary month indicating means, ratchet means operatively coupling said month indicating means, said ratchet means including a cam having a single actuating shoulder positioned to rotate in step with the numeral 31 of the number indicating means, year indicating counter means having a units member, year ratchet means coupling said units member to the month indicating means, said year ratchet means in-

cluding a cam having a single actuating shoulder positioned to rotate in step with the "December" indication of the month indicating means, and compensating means including a compensating pawl normally engaging the ratchet means of the number indicating means and arranged to move said ratchet means step by step in the direction of rotation of the number indicating means, electrically responsive means operatively associated with said compensating pawl to reciprocate the same on energization of the electrically responsive means, a single number contact making means mounted to rotate with the number indicating means, a plurality of short month contact bridging means including February contact bridging means, arranged to rotate in step with the month indicating means in a path common to all the short month contact bridging means, said February bridging means rotating in a parallel path, said contact bridging means being distributed about said path in conformity with the distribution of short month indicia on the month indicating means, a single rotary contact breaking means geared to rotate in 4 to 1 ratio with the month indicating means, an energizing circuit for the electrically responsive means including three pairs of normally open contacts arranged in the path of the contact making means and spaced correspondingly to the spacing of the numbers 29, 30 and 31 on the number indicating means, a pair of normally open short month contacts arranged in the path of the contact bridging means, a pair of normally open February contacts disposed adjacent the short month contacts in the path of the February contact bridging means, and a pair of normally closed leap year contacts disposed in the path of the contact breaking means and connected in series with the pair of normally closed short month contacts corresponding to the 29th.

2. In an electrically operated perpetual calendar having means for indicating week days, dates 1-31, months and years at a reading point, said first three means being carried by inner, intermediate and outer concentric shafts respectively and all said means being actuated in appropriate timed relationship by pawl means cooperating with ratchet wheels on said inner and intermediate shafts respectively, and electrical means for oscillating said pawl means; a mechanism for compensating for short months and leap years, said mechanism comprising a second pawl means cooperating with the ratchet wheel on said intermediate shaft, and a second electrical means for oscillating said pawl means; a contact arm carried by the shaft of the dates 1-31 indicating means, a pair of normally open 29th contacts, a pair of normally open 30th contacts and a pair of normally open 31st contacts fixedly arranged in spaced relationship in the path of the contact making arm to be successively bridged by said contact making arm when the respective numbers 29, 30 and 31 of the date indicating means are presented at the reading point, a rotary contact breaking member geared to the outer shaft in 4 to 1 ratio, a pair of normally closed leap year contacts fixedly mounted in the path of the contact breaking member and connected in series between said second electrical means and one of the contacts of the 29th pair, one of the contacts of the 30th pair being connected in parallel with one of the contacts of the 31st pair to said second electrical means to shunt said series connection,

a plurality of short month selector members extending outwardly from said outer shaft and including a February member, a pair of normally open short month contacts fixedly mounted in the path of the short month selector members, and a pair of normally open February contacts fixedly mounted adjacent the short month contacts in the path of the February member, the short month selector members and the February member being disposed to bridge the short month and February contacts when the corresponding month indicium of the month indicating means is presented at said reading point, one contact of the short month pair connected in parallel with one contact of the February pair to said second electrical means, the other contact of the short month pair being connected to the other contact of the 31st pair, the other contacts of the 29th and 30th pairs being connected in parallel to the other contact of the February pair.

3. In a perpetual calendar of the kind having rotary day, date, month and year indicating means interconnected so that the rotation of the date indicating means through one revolution causes rotation of the month indicating means through a step representing a month, and rotation of the month indicating means through a complete revolution causes rotation of the year indicating means through a step representing one unit, electrically operated date and leap year compensating means comprising auxiliary means for rotating the date indicating means step by step independently of the day indicating means, a solenoid means operatively coupled to said auxiliary means, a single date contact making means arranged to rotate with the date indicating means, a plurality of short month contact bridging means including a February contact bridging means, said short month contact and February contact bridging means being arranged to rotate with the month indicating means in a common path and distributed about said path in conformity with the distribution of short month indicia on the month indicating means, a single contact breaking member geared to rotate in 4 to 1 ratio with the month indicating means, an energizing circuit for the solenoid means including a pair of normally closed leap year contacts fixedly mounted in the path of the contact breaking member, a pair of normally open short month contacts fixedly mounted in the path of the short month contact bridging means, a pair of normally open February contacts fixedly mounted adjacent the short month contacts in the path of the February bridging means, a pair of normally open 29th date contacts, a pair of normally open 30th date contacts and a pair of normally open 31st date contacts, all said date contacts being fixedly mounted in the path of the contact making means to be successively contacted and closed thereby when the corresponding indication on the date indicating means is presented at a pre-determined reading point, one of the 29th date contacts being connected in series with the leap year contacts to one end of said solenoid means, one of the 31st date contacts being connected in parallel with one of the 30th date contacts to said one end of the solenoid means to shunt said series connection, the other of the 29th and 30th date contacts being connected in parallel to one of the February contacts, the other 31st date contact being connected to one of the short month contacts, the other short month

contact being connected in parallel with the other February contact to a terminal means, and the other end of said solenoid means being connected through a make and break device to a second terminal means.

5. In and for a perpetual calendar device, a main shaft, a day indicating means fast on the main shaft, a hollow intermediate shaft concentrically mounted for rotation on the main shaft, 10 a date indicating means fast on the intermediate shaft, an outer hollow shaft concentrically mounted for rotation on said intermediate shaft, a month indicating means fast on the outer shaft, ratchet and cam means operatively coupling the intermediate and outer shafts for step by step rotation of the outer shaft one step for every complete revolution of the intermediate shaft, a counting device, ratchet and cam means operatively coupling the outer shaft and the counting device for step by step actuation of the counting device one step for every complete revolution of the outer shaft, main ratchet means operatively associated with the main shaft and with the intermediate shaft for simultaneous step by step rotation of the main and intermediate shafts, and compensating means operated by the intermediate shaft for automatically compensating the date indication for leap years and for months having less than 31 days said compensating means including means rotating with said intermediate shaft for preparing additional rotational steps of said date indicating means, a power device controlled by said preparing means for advancing said date 25 indicating means through said additional steps, a selector rotated by said outer shaft to determine the making of one such prepared step by said power device in 30-day months and three such prepared steps in February, and a further 30 selector operated once in four years by said counting device to inhibit one of said three further steps in a leap year.
5. In a perpetual calendar of the kind having rotary day, number, month and year indicating 45 means interconnected so that the rotation of the number indicating means through one revolution causes rotations of the month indicating means through a step representing a month and rotation of the month indicating 50 means through a complete revolution causes rotation of the year indicating means through a step representing one unit, electrically operated number and leap year compensating means comprising auxiliary means for rotating the 55 number indicating means step by step independently of the day indicating means, electrically responsive means operatively coupled to said auxiliary means, a single number contact making means mounted to rotate with the number indicating means, a plurality of short month 60 contact bridging means including February contact bridging means, arranged to rotate in step with the month indicating means in a path common to all the short month contact bridging 65 means, said contact bridging means being distributed about said path in conformity with the distribution of short month indicia on the month indicating means, a single rotary contact breaking means geared to rotate in 1 to 4 ratio with the month indicating means, an energizing circuit for the electrically responsive means including three pairs of normally open contacts arranged in the path of the contact making means and spaced correspondingly to the spacing of the numbers 29, 30 and 31 on the num- 70 75

ber indicating means, a pair of normally open short month contacts arranged in the path of the contact bridging means, a pair of normally open February contacts disposed adjacent the short month contacts in the path of the February contact bridging means, and a pair of normally closed leap year contacts disposed in the path of the contact breaking means and connected in series with the pair of normally closed short month contacts corresponding to the 29th, the arrangement being such that connection of the normally open contacts corresponding to the 31st of a month by the contact making means is operative to energize the electrically responsive means to cause rotation of the number in-

15

dicating means through one step independently of the day indicating means when a short month contact bridging means cooperates with the short month contacts, and successive interconnection of the normally open contacts corresponding to the 28th and 29th of a month is similarly operative only when the February contact bridging means cooperate with the February contacts, and interconnection of the contacts corresponding to the 28th of a month is inoperative to energize the electrically responsive means when the contact breaking member cooperates with the normally closed leap year contacts.

JAIME ROITMAN.
